UNITED STATES PATENT OFFICE.

FRANK J. MULDOON, OF WEST BEND, WISCONSIN, ASSIGNEE OF ONE-HALF TO HENRY LOCHER, OF WEST BEND, WISCONSIN.

SPARK-PLUG.

1,182,297.

Specification of Letters Patent. Patented Dec. 29, 1914.

Application filed May 22, 1914. Serial No. 840,147.

To all whom it may concern:

Be it known that I, FRANK J. MULDOON, a citizen of the United States, and resident of West Bend, in the county of Washington and State of Wisconsin, have invented certain new and useful Improvements in Spark-Plugs; and I do hereby declare that the following is a full, clear, and exact description thereof.

10 My invention consists in what is herein particularly set forth with reference to the accompanying drawings and pointed out in the claim of this specification, its object being to provide simple, economical, durable and efficient non-fragile anti-leak spark-plugs that are proof against fouling and short-circuiting.

Further objects of my invention are to protect the electrode of each spark-plug 20 from sweat occurring in the remainder of said plug, and to prevent shifting of said electrode when fastening a terminal of an electric-circuit thereto.

Figure 1 of the drawings represents a 25 partly longitudinal section-view of one of my improved spark-plugs, the section being indicated by line 1--1 in Fig. 2, which Fig. 2, represents a plan view of the spark-plug inverted.

30 Referring by numerals to the drawings, 3 indicates the base, 4 the cap, 5 a filler, 6 the insulating core, 7 the electrode and 8 the base firing-points of my improved spark-plug.

35 The base 3 is a high-carbon steel shell having an outwardly hexagonal or otherwise angular outer end enlargement to take a wrench. The other end of the base is exteriorly screw-threaded to engage a correspondingly threaded opening in the 40 head of an internal-combustion engine-cylinder. The cap 4 is of vulcanized fiber and conical beyond a reduced cylindrical end that has screw-thread engagement with a socket in the enlarged end of the base. The

45 core 6 is a sleeve of mica central of the plug, and the electrode 7 of said plug extends through the outer end of the cap and said sleeve. The electrode is a brass-rod having an inner end firing-point 7' of platinum composition opposing the base firing-points 8 aforesaid, and said electrode is held in place by hexagonal or other suitable nuts

9 and 10 engaging a screw-thread thereof in position to bind against outer and inner surfaces of the cap. A thumb-nut 11 also 55 engages the screw-threaded end of the electrode to bind upon an electric-circuit terminal (not shown) interposed between it and the nut 9 aforesaid. The filler 5 is a fire-proof and oilproof plastic composition surrounding the insulating core 6 and baked or otherwise solidified in the base and cap aforesaid, said filler also serving as insulation. This filler is an important advantageous element of my improved spark-plug, 60 in that it prevents fouling and short-circuiting of the same, by making it impossible for carbon, metallic particles from an engine cylinder and piston, or oil mixed with bearing material to gather in said plug.

70 And because of said filler there is no need of removing the spark-plug from an engine for cleaning, but only to adjust the firing-points. The vulcanized fiber cap 4 is anti-leak and need not be removed after 75 the spark-plug is assembled. Being non-vitreous it is not liable to be broken by being hit with a wrench slipping off an adjacent spark-plug or other device, as would be the case were it of porcelain or other 80 vitreous material. By employing the nuts 9 and 10 in the arrangement shewn, the electrode 7 is prevented from shifting out of adjusted position when the terminal of an electric-circuit is fastened thereto, and 85 the thumb-nut 11 facilitates the placing of said terminal in connection with said electrode.

It is well known that spark-plugs sweat when engines to which they are connected are run warm and are let to cool, and the sweat coming into contact with the electrode of a spark-plug makes engine-starting difficult. My insulating core 6 is of such material and arrangement as to prevent sweat 95 of the remainder of the spark-plug from attacking the electrode thereof.

I claim:—

A spark-plug comprising a metallic base provided with firing-points, a non-metallic, 100 non-vitreous insulating cap; an electrode extending through the cap, nuts engaging the electrode against outer and inner surfaces of the cap, a binding nut engaging

the end of the electrode upon which the outer nut aforesaid is run, an insulating core through which the electrode also extends, and a filler of fireproof and oilproof plastic composition surrounding the core and solidified in said base and cap.

In testimony that I claim the foregoing

I have hereunto set my hand at West Bend in the county of Washington and State of Wisconsin in the presence of two witnesses. 10
FRANK J. MULDOON.

Witnesses:

HENRY KUESTER,
JULIUS GERMANSON.
